a. z. Vencill
BY His ATTORNEY.

UNITED STATES PATENT OFFICE

EARL M. ALLEN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

TRAIN INDICATING APPARATUS

Application filed September 26, 1930. Serial No. 484,563.

My invention relates to train indicating apparatus and has for an object the provision, in combination with a series of track sections, of novel and improved means for indicating at a remote point, such as a despatcher's office, the passage of trains through such sections.

I will describe one form of apparatus embodying my invention, and will then point out the novel features thereof in claims.

The accompanying drawing is a diagrammatic view showing one form of apparatus embodying my invention.

Referring to the drawing, the reference character Z designates a stretch of railway track which is divided by the usual insulated joints to form three successive sections A¹, A² and A³. Located in the section A² is a switch Q leading into a side track Z¹. Traffic through the switch Q is controlled by the usual signals S¹, S², S³ and S⁴, which signals are controlled by a signal relay D, and by a circuit controller U operatively connected with the switch Q. The circuits for the control of relay D, and the circuits for the control of the signals S, form no part of my present invention, it being sufficient to point out that when the relay D is energized in such direction that its polarized armature is swung to the left, one of the signals S³ or S⁴ will be cleared according as the switch Q is in the normal or the reverse position, and that when the relay D is energized in such direction that its polarized armature is swung to the right, one of the signals S¹ or S² will be cleared according as the switch Q is in the normal or the reverse position.

Each track section A¹, A² and A³ is provided with a track circuit comprising a track battery 2, and a track relay designated by the reference character T with a distinguishing exponent. Associated with these track relays and with the signal relay D, is a slow-releasing directional relay K, the control and purpose of which will be explained hereinafter.

Located at a remote point, such as a despatcher's office, is a group of indicator lamps L¹, L² and L³, corresponding to the track sections A¹, A² and A³, respectively. These

lamps are controlled by indicator relays C¹, C² and C³. Relay C² is a repeater for track relay T², the circuit being from terminal X of a suitable source of current, through front contact 13 of relay T², line wire 28, and the winding of relay C² to terminal O. Indicator relays C¹ and C³ are of a slow-releasing type, and are controlled by a polar relay E, which relay is in turn controlled by the track relays and by the directional relay K.

The directional relay K is normally energized by virtue of two pick-up circuits. The first of these circuits includes front contact 8 of track relay T¹, and the second includes the front point of contact 9 of track relay T³. These circuits will be obvious from the drawing without being traced in detail. Polar relay E is normally deenergized, and indicator relays C¹ and C³ are also normally deenergized. Indicator relay C², however, is normally energized. As explained herein-after, the indicator lamps L are controlled in such manner that, under the conditions just set forth, all of these lamps are extinguished.

I will first assume that a train moving toward the right enters section A¹. This will open track relay T¹, thereby closing a circuit for polar relay E, which circuit is from positive terminal N of a battery B, through the back point of contact 3 of relay T¹, front point of contact 4 of relay K, line wire 5, winding of relay E, and line wire 6 to the middle point of battery B. The current which is thus supplied to relay E is of what I will term "normal" polarity, and the effect of this current is to energize relay E in such direction that its polar contacts 16 and 18 are swung to the left. Indicator relay C¹ will then become energized, the circuit being from terminal X, through neutral contact 15 of relay E, polar contact 16, and the winding of relay C¹ to terminal O. Indicator lamp L¹ will then become lighted by virtue of a circuit which includes front contact 24 of relay C¹, and which circuit will be obvious from the drawing. When the front end of the train enters section A², track relay T² will open, thereby

- opening indicator relay C^2 , and this will cause lamp L^2 to become lighted by virtue of a circuit which includes back contact 23 of relay C^2 . When the rear end of the train 5 passes out of the section A^1 , track relay T^1 will close, thereby opening the circuit for polar relay E , so that the pick-up circuit for relay C^1 will be opened at neutral contact 15, with the result that relay C^1 will open 10 and lamp L^1 will become extinguished. Assuming that switch Q is in the normal position, so that the train will proceed on the main track Z , then when the front end of the train enters section A^3 , track relay T^3 15 will open, whereupon current of reverse polarity will be supplied to polar relay E . The circuit will then be from terminal R of battery B , through back contact 7 of relay T^3 , front point of contact 3 of relay T^1 , 20 front point of contact 4 of relay K , wire 5, winding of relay E and wire 6 to terminal O of battery B . This will cause relay E to become energized in such direction that its polar contacts will be swung to the right. 25 Indicator relay C^3 will then become energized by virtue of a pick-up circuit which passes from terminal X , through neutral contact 17 of relay E , polar contact 18, and the winding of relay C^3 to terminal O . Indicator lamp L^3 will then become lighted by virtue of a circuit which includes front contact 25 of relay C^3 and which circuit will be obvious from the drawing. When the rear 30 end of the train passes out of the section A^2 , track relay T^2 will close, thereby energizing indicator relay C^2 , with the result that indicator lamp L^2 will become extinguished. When the train passes out of section A^3 , track relay T^3 will become closed, so that the 35 circuit for relay E will be opened, and relay C^3 will become deenergized to extinguish the lamp L^3 .
- Under the conditions described in the last paragraph, the directional relay K will not 40 become deenergized, because one or the other of its pick-up circuits will be closed at all times; that is to say, either track relay T^1 or T^3 will be closed to close one pick-up circuit or the other.
- 45 I will now assume as before, that a train moving toward the right passes along the track Z , but that this train is long enough to bridge section A^2 , so that the front end of the train will enter section A^3 before the rear end leaves section A^1 . Under this condition both track relays T^1 and T^3 will be opened at the same time, so that both pick-up circuits for relay K will be simultaneously open. The stick circuit for this relay 50 includes contact 11 of signal relay D , and this contact will be open when either signal S^1 or S^2 is cleared to permit a train moving toward the right to pass through the switch Q . When this train enters section A^1 , it 55 will open track relay T^1 , thereby energizing relay E in the normal direction to close the pick-up circuit for relay C^1 . When the train enters section A^2 , it will open track relay T^2 , and this will open indicator relay C^2 . Indicator lamps L^1 and L^2 will then 70 both be lighted. When the front end of the train, which we have assumed to be long enough to bridge section A^2 , enters section A^3 , it will open track relay T^3 , and this will result in the opening of relay K . Current of reverse polarity will then be supplied to relay E , the circuit being from terminal R of battery B , through the back point of contact 4 of relay K , wire 5, winding of relay E , and wire 6 to terminal O of battery B . 80 This will result in closing the pick-up circuit for relay C^3 and opening the pick-up circuit for relay C^1 , so that indicator lamp L^1 will become extinguished and lamp L^3 will become lighted. When the rear end of the train passes out of the section A^1 , track relay T^1 will close, thereby closing relay K , but relay E will continue to be energized in the reverse direction, because the back contact 7 of track relay T^3 is closed. When the rear end of the train passes out of the section A^2 , track relay T^2 will close, thereby closing relay C^2 and extinguishing lamp L^2 . When the train passes out of the section A^3 , track relay T^3 will close, and the apparatus 95 will be restored to its normal condition.
- I will now assume that a train moving toward the left enters section A^3 . This will open track relay T^3 , thereby supplying current of reverse polarity to relay E , so that 100 lamp L^3 will become lighted. When the train enters section A^2 , it will open track relay T^2 , and this will open relay C^2 to light the lamp L^2 . If the train is not long enough to bridge section A^2 , then when the front 105 end enters section A^1 , the rear end will have left section A^3 , so that relay K will remain energized. The opening of relay T^1 will supply current of normal polarity to relay E , thereby energizing relay C^1 to light lamp L^1 . When the train leaves section A^2 , lamp L^2 will become extinguished, and when the train leaves section A^1 , lamp L^1 will become extinguished.
- I will now assume that a train moving 115 toward the left is long enough to bridge section A^2 . In order to permit this train to pass through the switch Q , relay D will be energized in such direction that its polar contact 11 will be closed. When the train enters section A^3 , the opening of track relay T^3 will energize relay E in the reverse direction to energize relay C^3 and so as to light lamp L^3 . When the train enters section A^2 , the opening of track relay T^2 will cause indicator lamp L^2 to become lighted. A stick circuit for relay K will now be closed, which circuit is from terminal X , through the back point of contact 9 of track relay T^3 , back contact 10 of track relay T^2 , contact 11 of 125

relay D, front contact 12 of relay K, and the winding of relay K to terminal O. When the front end of the train enters section A¹, it will open track relay T¹, but this will not open relay K, because of the stick circuit which has just been traced. Current of normal polarity will then be supplied to relay E through the back point of contact 3 of track relay T¹ and the front point of contact 4 of relay K, with the result that relay C³ will become open to extinguish lamp L³, and relay C¹ will become energized to light lamp L¹. When the rear end of the train leaves section A², lamp L² will become extinguished, and when the train leaves section A¹, lamp L¹ will become extinguished.

I will now assume that a train moving toward the left enters section A³, thereby energizing relay E in the reverse direction which then causes relay C³ to become energized, and that while this train occupies section A³ a second train moving toward the right enters section A¹. The stick circuit for relay K is already open at back contact 10 of track relay T² since section A² is unoccupied, and the pick-up circuit for relay K through contact 9 of relay T³ is already open on account of the train in section A³. On account of the train now entering section A¹, the other pick-up circuit for relay K becomes opened at contact 8 of relay T¹, and hence relay K becomes deenergized. Relay K being of a slow-releasing type does not, however, at once open its contacts 12 and 4. Meanwhile, relay E becomes energized in the normal direction by its circuit including the back point of contact 3 of relay T¹ and the front point of contact 4 of relay K. Upon this reversal of polarity of current supplied to relay E, contact 17, as well as contacts 15 and 26, of relay E open, polar contact 18 of relay E is then swung to the left and contact 17 then again closes. Relay C³ being of a slow-releasing type does not open its contacts 22 and 25 during this open period of contact 17 of relay E. When contact 17 closes after contact 18 has been swung to the left, relay C³ is energized by a stick circuit which passes from terminal α , through contact 17 of relay E, contact 18 of relay E in its left position, front contact 21 of relay C², front contact 22 of relay C³, and the winding of relay C³ to terminal o. With relay E energized in the normal direction, relay C¹ has become energized to light the indicator lamp L¹. Upon the lapse of a sufficient period of time after the opening of contact 8 of relay T¹, relay K opens its front contacts and closes contact 4 at its back point thereby causing relay E to be again energized in the reverse direction. Upon this reversal of polarity of the current supplied to relay E, contact 15, as well as contacts 17 and 26, of relay E opens, polar contact 16 is then swung to its position toward the right

and contact 15 then again closes. Relay C¹ being of a slow-releasing type does not open its front contacts during this open period of contact 15. Upon the closing of contact 15 after contact 16 has been swung to its right position, relay C¹ becomes energized by a stick circuit passing from terminal α , through contact 15 of relay E, contact 16 of relay E in the right position, front contact 19 of relay C², front contact 20 of relay C¹, and the winding of relay C¹ to terminal o. It follows that lamp L³ has remained lighted to indicate the presence of a train in section A³, and that lamp L¹ now also remains lighted to indicate the presence of a train in section A¹. The subsequent operation of the indicator lamps will depend upon the movements of the two trains. If the train in section A¹ proceeds into section A², track relay T² will open, thereby opening relay C² and thus opening the stick circuit for relay C¹ so that lamp L² will become lighted and lamp L¹ will be extinguished.

Finally, I will assume that section A¹ is occupied by a train, and that a second train enters section A³. Relay E will be energized in the normal direction, due to the presence of the train in section A¹, so that relay C¹ will be energized and lamp L¹ will be lighted. When the second train enters section A³, the opening of track relay T³ will deenergize relay K, so that current of reverse polarity will be supplied to relay E. The stick circuit for relay C¹ will then become closed, and relay C¹ will, therefore, remain energized to keep lamp L¹ lighted, whereas relay C³ will also become energized to light lamp L³. The lamps will, consequently, indicate the presence of the two trains in sections A¹ and A³, respectively.

Each time that relay E becomes energized, an annunciator bell F will be energized, the circuit being from terminal X, through front contact 26 of relay E, back point of contact 27 of a relay G, and the bell F to terminal O. The despatcher may stop the operation of the bell by closing a push button H, thereby closing the pick-up circuit for relay G, which circuit will be obvious from the drawing. Relay G will then remain energized as long as relay E is energized, this being due to a stick circuit which includes front contact 26 of relay E, and the front point of contact 27 of relay G. When relay E becomes deenergized, the stick circuit for relay G will be opened, so that the apparatus is again ready for the operation of bell F when relay E again becomes energized.

It will be seen from the foregoing that apparatus embodying my invention provides for the continuous indication of the presence and absence of trains in three successive sections of track, and that this is

accomplished by only three wires between the track and the despatcher's office.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, three sections of railway track, a polar relay, means for energizing said relay in one direction or the other according as the first or the third of said sections is occupied by a train, an indicator for each of said sections, means for energizing the indicator for the first or the third section according as said relay is energized in one direction or the other, and means for energizing the indicator for the second section when the second section is occupied.

2. In combination, two spaced sections of railway track, a polar relay, means for energizing said relay in normal or reverse direction according as one or the other of said sections is occupied by a train, two slow-releasing indicator relays, a pick-up circuit for one indicator relay including a normal contact of said polar relay, a stick circuit for said one indicator relay including a reverse contact of said polar relay, a pick-up circuit for the other indicator relay including a reverse contact of said polar relay, a stick circuit for said other indicator relay including a normal contact of said polar relay, and indicators for said track sections controlled by said indicator relays.

3. In combination, three sections of railway track, a polar relay, means for energizing said relay in normal or reverse direction according as the first or the third of said sections is occupied by a train, a first and a third slow-release indicator relay, a pick-up circuit for the first indicator relay including a normal contact of said polar relay, a pick-up circuit for the third indicator relay including a reverse contact of said polar relay, a second indicator relay for the second of said sections, means for energizing or deenergizing said second indicator relay according as said second section is unoccupied or occupied, a stick circuit for said first indicator relay including a reverse contact of said polar relay and a front contact of said second indicator relay, a stick circuit for said third indicator relay including a normal contact of said polar relay and a front contact of said second indicator relay, and indicators for said track sections controlled by said indicator relays.

4. In combination, three sections of railway track, a track circuit including a track relay for each section, a directional relay,

means for energizing said directional relay when either the first or the third track relay is closed, a stick circuit for said directional relay closed only when the second and third track relays are open and traffic is established for train movements from the third section toward the first, and train indicators located at a remote point from said track sections and controlled by said track relays and directional relay.

5. In combination, three sections of railway track, a track circuit including a track relay for each section, a directional relay, means for energizing said directional relay when either the first or the third track relay is closed, a stick circuit for said directional relay closed only when the second and third track relays are open and traffic is established for train movements from the third section toward the first, a polar relay, means for energizing said polar relay in normal or reverse direction according as said first or third track relay is open, provided said directional relay is closed and for energizing the polar relay in reverse direction when the directional relay is open, two slow-releasing indicator relays, a pick-up circuit for one indicator relay including a normal contact of said polar relay, a stick circuit for said one indicator relay including a reverse contact of said polar relay, a pick-up circuit for the other indicator relay including a reverse contact of said polar relay, a stick circuit for said other indicator relay including a normal contact of said polar relay, and indicators for said track sections controlled by said indicator relays.

6. In combination, three sections of railway track, a track circuit including a track relay for each section, a directional relay, means for energizing said directional relay when either the first or the third track relay is closed, a stick circuit for said directional relay closed only when the second and third track relays are open and traffic is established for train movements from the third section toward the first, a polar relay, means for energizing said polar relay in normal or reverse direction according as said first or third track relay is open, provided said directional relay is closed and for energizing the polar relay in reverse direction when the directional relay is open, an indicator relay for each section, means for energizing the indicator relay for the first or the third section according as said polar relay is energized in normal or reverse direction, means for energizing the indicator relay for the second section when and only when the second track relay is energized, a stick circuit for the first indicator relay including a reverse contact of said polar relay and a front contact of said second indicator relay, a stick circuit for

the third indicator relay including a normal contact of the polar relay and a front contact of the second indicator relay, and indicating means for the sections controlled by 5 said indicator relays.

In testimony whereof I affix my signature.

EARL M. ALLEN.
